UNITED STATES PATENT OFFICE.

SAMUEL J. OLSHIN, OF YONKERS, NEW YORK.

SKYLIGHT.

Application filed November 5, 1921. Serial No. 512,998.

To all whom it may concern:

Be it known that I, SAMUEL J. OLSHIN, a citizen of the United States, residing at Yonkers, in the county of Westchester and 5 State of New York, have invented certain new and useful Improvements in Skylights, of which the following is a specification.

This invention relates to a skylight of the type that can be opened when desired for 10 ventilation purposes and will be automatically opened in case of fire. It is especially adapted for theater stage purposes but is not restricted to such use.

It is frequently desired, or required by 15 municipal regulations, that the area of space that is open when the windows or sashes of a skylight are in their open position shall at least be equal to the opening in the roof over which the skylight is installed. It is also desired 20 that the windows or sashes be capable of being opened partially or entirely in a very prompt and certain manner, whenever occasion demands. Also, in case of fire, the opening of the sashes should take place 25 promptly and automatically in case the temperature exceeds a certain amount, and should be easily and quickly effected whenever an emergency arises in which it is desirable to open the skylight. These and 30 other useful objects are accomplished by this invention without requiring the installation of complicated devices that are apt to get out of fix and become inoperative.

The invention will be understood from 35 the description and drawings illustrating an embodiment thereof, in which the same reference characters refer to the same parts throughout. In the drawings

Fig. 1 is an end view of the skylight with 40 parts left off.

Fig. 2 is a view showing a sash with its hinge connection.

Fig. 3 is a side view corresponding to Fig. 2.

Fig. 4 is a side view of a modification of 45 the hinge connection, and

Fig. 5 is a plan view of the same.

Reference character 1 indicates the roof over the opening 2 in which the skylight 3 is installed. The skylight 3 comprises the ordinary covering 4 and sides 5, having cross beams 6 and 7. At the sides and ends are mounted windows or sashes 8 of the requisite number and size that the conditions 55 render necessary or advisable.

The sashes 8 are so installed that they

form substantially vertical walls for the skylight and are so mounted or pivoted or hinged that their tendency is to turn outwardly by their own weight to open the 60 spaces which they cover in their normal closed position. For this purpose the windows or sashes 8 may be mounted and fastened in a longitudinal groove 9 along the upper edge of a metal strip 10, which strip 65 is bent to provide an outstanding portion 11 that is pivoted to uprights 12 resting on cross-beam 7. The extreme edge of the sheet 10 may be bent around a rod 13 that passes through holes in the uprights 12 so as to 70 form a hinged or pivoted connection. Other convenient ways may be used for providing a pivoted connection for the sash 8, the important consideration being that the center of gravity of the sash 8 should be so related 75 to the pivot point about which it swings that the sash will open automatically when the means for holding it in its closed position is released.

Pins 15 are attached to the sashes 8 and 80 are connected by strands or cords 16 which pass over pulleys 17 to a rope 18, which is provided with a fusible link 19. When the rope 18 is taut, the sashes 8 are turned to their closed vertical positions with their upper edges extending under the overhanging projections 4'. When the rope 18 is loosened by severing it or unfastening its lower end, or by fusing the link 19, the sashes 8 turn about their pivot points, being impelled by 90 their weight, thus opening the skylight.

Instead of having the sashes 8 fastened to metal strips as above indicated, they may be attached to bracket arms 20 (Figs. 4 and 5) whose ends 21 are bent and are pivoted to 95 supports 22. A rod 23 extends through holes in the portion 21 and support 22 and serves as a pivot for the bracket 20. Other changes and modifications may be made without departing from the spirit or scope of the invention as set forth in the appended claims.

Having described my invention, what I claim as new and desire to secure by Letters Patent is:

1. In a device of the class described, a sash 105 substantially vertical in its normal closed position, a housing, said sash being outside of said housing, a pivot for said sash inside of said housing, said sash being connected to said pivot by an offset portion.

2. In a device of the class described, a sash, a pivot therefor, a wall, said sash be-

ing on one side of said wall and said pivot on the other side of said wall.

3. In a device of the class described, a sash, a pivot therefor, said sash being connected to said pivot by means of a bent sheet of stiff material.

4. In a device of the class described, a

substantially vertical sash, a wall, an offset member connected to said sash whereby said sash is pivoted on the opposite side of said wall from said sash.

In testimony whereof I affix my signature.

SAMUEL J. OLSHIN.
